UNITED STATES PATENT OFFICE.

HENRY C. SCHUMACHER, OF BARBERTON, OHIO, ASSIGNOR TO THE DIAMOND MATCH COMPANY, OF CHICAGO, ILLINOIS, A CORPORATION OF ILLINOIS.

TRAY-FEEDING MECHANISM FOR BOX-FILLING MACHINES.

1,415,900.

Specification of Letters Patent.

Patented May 16, 1922.

Application filed December 26, 1919. Serial No. 347,302.

To all whom it may concern:

Be it known that I, HENRY C. SCHUMACHER, a citizen of the United States, and resident of Barberton, in the county of Summit and State of Ohio, have invented certain new and useful Improvements in Tray-Feeding Mechanisms for Box-Filling Machines, of which the following is a specification.

This invention relates to machines for filling box trays with matches and other articles, and has reference more especially to mechanism for feeding the trays in succession to the tray conveyer of such machines.

The object of the invention is to accomplish the feeding of the box trays with rapidity and accuracy to the tray conveyer and thereby permit the travel of the latter at a relatively higher speed than formerly across the source of article supply, thus securing correspondingly increased production.

To this end, the invention comprises novel features of construction and combinations of parts which will be hereinafter described, the precise scope of the invention being pointed out in the appended claims.

In the drawings—

Figure 1 is a plan of tray-feeding mechanism embodying my invention.

Fig. 2 is an end elevation of the same.

Fig. 3 is a side thereof.

Fig. 4 is a detail of the auxiliary gear connection between the tray feeding wheel and the shaft of the tray conveyer.

Figs. 5 and 6 are sections through the slip connections of the gearing on the feed wheel and conveyer shafts, respectively.

Referring to the drawings, 20 designates a horizontal bed or table supported adjacent the delivery portion of a match making machine, and 21 designates an endless box-tray conveyer arranged to travel on the bed across the path of the matches being discharged from the machine. This conveyer passes about sprocket-wheels at or near the respective ends of the bed, one of which wheels is indicated at 22. The shaft 23 of this wheel is provided with a bevel gear wheel 24 in mesh with a similar wheel 25 on a short shaft 26 extending longitudinally of and beneath the bed, which latter shaft bears a spur wheel 27 in mesh with a pinion 28 on a main drive shaft 29. This drive shaft, which is journaled in bearings beneath the bed, is continuously driven from a suitable

source of power, thereby imparting continuous motion to the tray conveyer through the gearing described.

The form of tray conveyer illustrated comprises metal links jointed together to constitute an endless chain having outwardly extending walls 29 which provide jaws by and between which the match box trays (a) are held and thus transported in proximity to the source of match supply.

In accordance with my invention the trays are fed to the successive links of the match conveyer by mechanism of the following construction:

30 designates a substantially vertical chute body having at its lower end a curved portion 31 which leads toward and terminates immediately in advance of the tray conveyer as the latter approaches its upper horizontal path at the receiving end of the machine. The trays entered side by side in the upper end of the chute body gravitate to its lower end and are gradually turned to a position with their bottoms downward as they pass along the curved lower portion of the chute. In this condition they are consecutively advanced beyond the chute and positioned transversely of and between succeeding pairs of jaws of the conveyer, by means of a rotating feed wheel 32, which is mounted to overhang the delivery end of the chute. This wheel is provided with a regularly spaced series of peripheral tappets 33 which, in the rotation of the wheel, engage the bottom and the inner forward walls of the leading trays in succession.

The tappets are so spaced apart that when one engages and advances with the bottom and wall of the leading tray at the foot of the chute the immediately preceding tappet 95 in its upward travel contacts with the opposing jaw of the tray conveyer and advances concurrently with the latter. Preferably each of the tappets is provided with a yielding facing, 34, of leather or the like 100 which acts as a pad upon the opposing bottom of the tray.

The wheel 32 is fast on a shaft 35 having its bearings in suitably-disposed brackets 36, which shaft bears a pinion 37 in mesh with a spur wheel 38 fast on the conveyer shaft 23. The normal action of the gearing is to rotate the feed wheel at a higher speed than the conveyer and thus tend to press the successively advancing tappets against the op-

posing jaws of the progressing conveyer. In order to retard the rotation of the feed wheel and ensure its movement correspondingly with the speed of the conveyer, a suitable slip connection is provided between the pinion 37 and the shaft 35. This connection, in the present instance, is attained by loosely mounting the pinion 37 on the shaft 35 between a pair of friction washers 39 on the latter, whereof one washer bears against a collar 40 on the shaft, while the other is adjustably held against the opposing face of the pinion by a clamp washer 41 and adjusting screw 42. A tray feeding mechanism 15 substantially of the character just described is set out in the Donnelly Patent No. 1,386,243, dated August 2, 1921, and is therefore not broadly claimed by me.

To ensure the accurate positioning of the 20 tappets in relation to the proximate trays and the respective jaws of the conveyer, I provide a novel auxiliary gear connection or compensator, between the tappet wheel and the conveyer shaft 23, which connection comprises two co-acting gear wheels 43, 44 respectively, having hook-form intermeshing teeth. In the present instance the wheel 43 is attached to a flange 45 on the hub 46 of the tappet wheel by means of screws 47 25 passing into the wheel 43 through arcuate slots 48 in the flange, and thereby the wheel 43 can be nicely adjusted about its axis and secured in a position which insures the proper relative location to each other of the inner 30 termeshing teeth of the respective wheels 43, 44. The wheel 44 is impositively secured to the shaft 23 by a suitable slip connection 49 such as that described in respect to the pinion 37 and the shaft 35, which connection 35 permits variable motion between the wheels 43, 44 in accordance with that of the feed wheel as above described.

The upper portion of the vertical chute 30 curves upwardly and outwardly, as at 50, 45 and terminates in a horizontal extension 51 to which the trays are successively delivered in side to side relation to each other and thence fed to the vertical body of the chute. The means for thus supplying the trays to 55 the chute extension comprises a horizontal belt 52 the upper run of which extends at right angles to and in proximity to the floor of said extension, the side wall of the chute being suitably cut away, as at 53, to permit 60 the passage of the trays to the extension. This belt passes about suitably-disposed pulleys 54, 55 respectively, one of which is fast on a shaft 56 having its bearings in a bracket 57 adjacent the chute, and the other of which 65 turns loosely on a shaft 58 supported by a bracket 59, said brackets 57, 59 being mounted on a suitable frame structure 60. The shaft 56 bears a bevel gear wheel 61 in mesh with a similar wheel 62 on a short shaft 63 having its bearings in a bracket 64 on the

frame structure 60. This shaft 63 is provided with a pulley 65 which is connected by means of a belt 66 with a pulley 67 on a lower shaft 68 having its bearings in a bracket 69 on the end of the bed 20. The 70 shaft 68 is also equipped with a gear wheel 70 in mesh with a wheel 71 at one end of an adjacent shaft 72. On the opposite end of the latter shaft is a pinion 73 in mesh with the spur wheel 38 on the conveyer shaft. By 75 the system of gearing above described continuous motion is transmitted from the conveyer shaft 23 to the shaft 56, and thus the belt 52 is impelled with its upper run moving toward the chute. Hence box trays 80 imposed end to end on the belt are advanced thereby toward the horizontal extension 51 of the chute. Preferably the upper run of the belt 52 is flanked by a pair of guide belts 74, which are spaced apart to engage the 85 ends of the row of trays on the belt 52, and contribute to their rapid and uniform advancement to the said chute extension. The belts 74 pass about suitably-disposed pulleys 75, the shafts 76 of which have their bearings in a bed 77 supported on the brackets 57, 59. The shafts 76 adjacent the chute extension are equipped with bevel gear wheels 78 which mesh with similar wheels 79 on the shaft 56, thereby impelling the belts 74 concurrently with the belt 52. The inner runs of the belts 74 are supported by longitudinal backer strips 80 on the bed 77.

In order to promote the orderly progression of the row of trays on the belt 52, I 100 preferably provide a gravity pressure bar 81 which overhangs and extends longitudinally of the row, the outer end of the bar being pivotally supported in and between a pair of brackets 82 on the bed 77.

The trays of the row are successively advanced into and across the chute extension 51, each tray when thus delivered being pushed along the extension and toward the depending body of the chute by means of a 110 reciprocating head 83 which is mounted in suitable guide ways 84 at the outer end of the chute extension. The head 83 is connected by means of a link 85 to a crank-disk 86 fast on one end of a short shaft 87 which 115 has its bearing in a bracket 88 on the chute. Fast on the other end of the shaft 87 is a sprocket-wheel 89 which is connected with and driven from a similar wheel 90 on the shaft 68 by means of a chain 91. The ratio 120 of the gearing is such that as each leading tray is delivered to the chute extension, the head 83 is caused to impinge against such tray and advance it along the extension. When the head 83 bridges the opening 53 the 125 feeding of the trays to the chute extension is temporarily checked, in which case the belts 52, 74 move idly in contact with the trays; but when the head is retracted the next leading tray is advanced through the opening 130

and into the chute extension. This tray is then advanced by the reciprocating head, and thus the trays are successively delivered to the horizontal chute extension, and pushed 5 therealong side by side.

It is to be understood that my invention is not limited to the details of construction disclosed, as the same may be modified within the principle of the invention and the 10 scope of the appended claim.

I claim—

1. The combination with a conveyer having a succession of tray holders comprising spaced transverse walls, and means for impelling the conveyer, of means for feeding trays successively adjacent the receiving end of the conveyer, a rotary feed-wheel overhanging the receiving end of the conveyer and having spaced tappets which contact 15 with the inner forward walls of the succeeding leading trays and also with the succeeding opposing walls of the tray holders, im- 20 positive means for actuating said wheel at a normally higher speed than the conveyer, and a connection between said impositive means and the said conveyer impelling means 25

whereby the accurate positioning of the tappets in relation to the proximate trays and the respective walls of the conveyer is maintained.

2. The combination with a conveyer having a succession of tray holders comprising spaced transverse walls, and means, including a positively driven shaft, for impelling the conveyer, of a chute for feeding trays 30 successively adjacent the receiving end of the conveyer, a rotary feed-wheel overhanging the receiving end of the conveyer and having spaced tappets which contact with the inner forward walls of the succeeding leading 35 trays and also with the succeeding opposing walls of the tray holders, means, including a shaft having a slip connection, for actuating said wheel at a normally higher speed than the conveyer, and an auxiliary 40 impositive gear connection between the shaft of the conveyer impelling means and the said wheel.

Signed at Barberton, in the county of Summit and State of Ohio, this 17th day of 50 December, A. D. 1919.

HENRY C. SCHUMACHER.
